UNITED STATES PATENT OFFICE.

GEORGE R. SHANKLIN, OF SPRINGFIELD, ILLINOIS.

VALVE STRUCTURE FOR ACETYLENE-LAMPS AND THE LIKE.

1,334,505.

Specification of Letters Patent. Patented Mar. 23, 1920.

Application filed May 7, 1918. Serial No. 233,020.

To all whom it may concern:

Be it known that I, GEORGE R. SHANKLIN, a citizen of the United States, residing at Springfield, in the county of Sangamon and State of Illinois, have invented 5 certain new and useful Improvements in Valve Structures for Acetylene-Lamps and the like, of which the following is a description.

10 My invention belongs to that general class of valve devices particularly designed to control the flow or feed of the fluid to the calcium carbide in acetylene lamps and equivalent devices. It has for its object the 15 production of a simple and effective valve device for the purpose stated, which is not liable to clog up with use but is reliable and durable in its operation.

To this end my invention consists in the 20 novel construction, arrangement and combination of parts herein shown and described, and more particularly pointed out in the claims.

In the drawings, wherein like reference 25 characters indicate like or corresponding parts,

Figure 1 is a vertical section of a miner's acetylene lamp, equipped with my invention;

30 Fig. 2 is an enlarged vertical section of the lower end of the tube and a valve co-operating therewith.

Fig. 3, is a transverse section on the line 5—5 of Fig. 2.

35 Fig. 4 is a transverse section on lines 6—6 of Fig. 2.

Fig. 5, is a vertical section of a slightly different form of tube and valve mechanism.

40 Fig. 6 is a transverse section on the line 3—3 of Fig. 5.

In the drawings, 1 is the upper part of a water chamber of a miner's lamp of the character described, provided with the filling opening 3 having a cover or cap 4. A centrally disposed tube 5 extends from the top of the chamber 1 downward through the bottom 6, and a considerable distance into the carbide chamber 7. As is usual in 45 devices of this kind, the shell or chamber 1 is provided with a depending screw threaded section 8 which is engaged by a co-operating section 9 on the carbide chamber 7.

50 The lower end of the tube 5 is formed with a valve seat 10 on the end thereof,

A section 11 has formed upon its upper face a co-operating part adapted to seat upon the valve seat 10. The lower end of the section 11, as at 13, has also formed upon it a valve seat arranged to co-operate with the valve 14. A valve stem 15 carried upon the top of the water chamber 1 loosely extends within the tube 5 and the section 11, and is firmly attached to the valve 14. 60 The upper portion of the valve stem is preferably bent as at 16 to form a convenient handle by means of which the valve stem can be rotated. The stem is carried by a sleeve 17, for movement therewith, 70 said sleeve being screw threaded into the upper end of the tube 5 as at 18. It will be readily seen that upon rotating the valve stem 15, the valve 14 will be caused to approach or recede from the end of the 75 tube 5. The valve stem loosely passing through the section 11, permits said section to readily leave the seat 10 as the stem is rotated to open the valve. At the same time said section resting loosely on the 80 valve, readily permits the escape of the fluid also by the seat at 13, where said valve 14 engages therewith. It will be seen that when the valve is open the fluid readily escapes, both at the point 10—12 and at the 85 point 13—14. The fluid enters the tube through openings formed therein as at 19.

As thus described the device is substantially the same as that illustrated in the patent heretofore issued to F. Guy, No. 90 1,198,537.

My improvement upon this form of device consists in combination of an inclosing sleeve 20 rigidly secured to the section 11, and within which the valve 14 is loosely 95 positioned so as to readily rotate therein. The lower end of the sleeve extends well below the lower face of the valve, and as the valve stem extends loosely through said section, the rotation of the valve stem is 100 not transmitted to said section and sleeve. Therefore, the movement of the valve does not agitate or affect the carbide within the chamber 7 the sleeve constituting a housing or protecting medium for the valve, and 105 the sleeve being adapted to rest upon the carbide spaced from the bottom of the container, and offering substantially no lateral obstruction beyond the wall of the tube 19. The sleeve does not prevent the ready 110 escape of the water between the valve and its seat 13, nor between the upper end of

the section 11 and its seat 10. In that embodiment of the invention illustrated in Figs. 1 to 4 inclusive, the sleeve 20 is extended upward above the section 11 as at 5 21, while preferably slotted apertures 22 are formed in the sleeve in line with the meeting of the upper edge of said section, and its valve seat 10, with apertures 23 likewise formed in line with this point of contact of 10 the valve 14 with the valve seat 13 on the lower end of said section. The slots 23 may be dispensed with if desired, although preferred, but if the sleeve 20 extends above the point 12-10, it is desirable to form 15 slots or equivalent openings in the sleeve to permit the fluid to escape therethrough.

This form of the invention has certain advantages in addition to those represented by that embodiment of the invention illustrated in Figs. 5 and 6, in which the upward extension of the sleeve 11 is dispensed with. In both forms of construction, in operation, assuming that the sleeve 20 rests upon the bed of carbid, the effect will be 20 simply to allow the valve to descend slightly within the sleeve without in any way moving or agitating the latter. In such case, the section 11 may or may not descend sufficiently to allow fluid to escape to any material extent between the section 11 and seat 25 10. If the sleeve 20 is not firmly seated upon the carbid, it, together with the section 11 to which it is attached, will drop slightly by force of gravity permitting the 30 fluid to escape at both ends of the section 11. The operator when he removes the bottom 7 of the carbid container for a fresh supply of calcium carbid may with his thumb and finger rotate the section 11 and 35 sleeve 20, thus serving to free the valve and its connected parts as well as the valve seats from all of the accumulation of the slacked carbid.

Having thus described my invention, it is 40 obvious that various immaterial modifications may be made in the same without departing from the spirit of my invention, hence I do not wish to be understood as limiting myself to the exact form, construction, arrangement and combination of parts herein shown and described or uses mentioned.

What I claim as new and desire to secure by Letters Patent is:

1. In a device of the kind described, a vertical fluid tube provided with a valve seat upon its lower end, and a loosely seated section having a coöperating valve face upon its upper end and a valve seat on its lower end, in combination with a rotatable valve 55 stem having a valve upon the lower end thereof adapted to seat upon the valve seat on said section, and a depending sleeve secured to said section and loosely inclosing the valve, substantially as described.
- 60 2. In a device of the kind described, a vertical

tube adapted to convey liquid and having formed upon its free end a valve seat, a rotatable section having formed upon its upper end a valve face adapted to coöperate with said seat, and a valve seat upon its lower end, and a depending sleeve secured to said section and extending below the valve, in combination with a valve stem loosely positioned within the tube and section and carrying upon its free end a valve 75 formed to be loosely positioned within the sleeve and operable with the valve seat upon the end of said section, substantially as described.

3. In a device of the kind described, a depending fluid tube having a valve seat formed upon the free end thereof, a coöperating section therefor having a valve face formed upon its upper end arranged to coöperate with said seat, and having its lower end provided with a valve seat, and a sleeve secured to said section and extending both above and below the same, loosely embracing the tube and provided with openings therein substantially in line with the meeting of the upper 90 end of said section with the lower end of the tube, in combination with a rotatable valve stem loosely positioned within the tube, and said section, and provided upon its free end with a valve 14 rotatable within 95 the sleeve and adapted to coöperate with the valve seat upon the lower end of the sleeve, substantially as described.

4. A device of the kind described comprising a depending tube provided with a valve 100 seat upon its lower end, a coöperating section therefor having a valve face upon its upper end for said valve seat, and a valve seat upon its lower end, and a sleeve secured to said section and extending both 105 above and below the same, in combination with a rotatable valve stem located within the tube and loosely extending through said section, provided upon its free end with a valve arranged to coöperate with the valve 110 seat on said section, said sleeve loosely embracing both the tube and valve and projecting a substantial distance below the latter whereby the valve offers no obstruction 115 beyond the lower edge of the sleeve.

5. In a device of the kind described, a vertical fluid tube, a valve stem loosely projecting through the tube and terminating at its lower end in a valve part, the valve stem having connected thereto a threaded 120 part, and the tube having a coöperating threaded support for said stem, the lower end of the tube forming a valve seat, a tubular valve section sleeved upon the valve stem and having an upper valve face to coöperate with the seat at the lower end of the tube, said tubular valve section forming at its lower end a valve seat for the valve part at the lower end of the stem, and means supported wholly from said tubular valve 125 130

section to rest upon carbid or the like, and space the valve therefrom, comprising a sleeve secured to the tubular valve section and of a length to project a substantial distance below the valve, with no parts of the latter offering an obstruction beyond the lower edge of said sleeve.

6. In a device of the kind described, the combination of a vertical tube adapted to 10 convey liquid to carbid, said tube being stationary and terminating at its lower end in a valve seat, a valve stem mounted for rotatable and lengthwise movement loosely projecting through said tube and terminating 15 at its lower end in a valve spaced below said valve seat, a valve section positioned on the stem and interposed between the valve seat of the tube and said valve, and a tubular member secured to said valve section 20 overlying the side of the valve stem and projecting a sufficient distance below the valve to space the same from the carbid, the valve section and sleeve being fixed to one another and adapted to be subjected to rotatable 25 movement independent of the stem and its valve.

7. In a device of the kind described, a container, a vertical fluid tube supported from the top of the container and provided 30 with a valve seat upon its lower end and a loosely seated section of substantially the same diameter as the tube having a coöperating valve face upon its upper end and a valve seat on its lower end, in combination 35 with a rotatable valve stem having a valve upon the lower end thereof adapted to seat

upon the valve seat on said section, and offering no lateral projection beyond said section, and a depending tubular sleeve secured to said section and loosely inclosing the 40 valve, said sleeve having an open end and projecting downwardly below the valve and spaced upwardly from the base of the container.

8. In a device of the kind described, a 45 container, a vertical fluid tube depending from the top of the container and provided with a valve seat upon its lower end, a loosely seated section of substantially the same diameter as the tube having a valve 50 face upon its upper end to engage the valve seat of the fluid tube, and said section having a valve seat on its lower end, in combination with a rotatable valve stem having a valve upon the lower end thereof adapted 55 to seat upon the valve seat of said section and offering no substantial lateral projection beyond said section, and a depending tubular sleeve secured to said section, and loosely inclosing the valve, said sleeve having 60 an open end and projecting downwardly below the valve and spaced upwardly from the base of the container, and said sleeve also having peripheral openings adjacent the top and bottom of said section. 65

In testimony whereof, I have hereunto signed my name in the presence of two subscribing witnesses.

GEORGE R. SHANKLIN.
